DESIGN FOR A COMBINED DISPLAY CASE AND COUNTER

Laurence R. Silveira, Oakland, Calif.

Application April 5, 1946, Serial No. 128,314

Term of patent 3½ years

(Cl. D80—11)

To all whom it may concern:

Be it known that I, Laurence R. Silveira, a citizen of the United States, residing at Oakland, in the county of Alameda and State of California, have invented a new, original, and ornamental Design for a Combined Display Case and Counter, of which the following is a specification, reference being had to the accompanying drawing, forming part thereof.

The figure is a frontal perspective view of a combined display case and counter, showing my new design.

I claim:

The ornamental design for a combined display case and counter, as shown.

LAURENCE R. SILVEIRA.
